(57) **CLAIM**

The ornamental design for an earphone, as shown and
described.

DESCRIPTION

FIG. 1 is a left, front, and top perspective view of an
earphone showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in the drawings are for the purpose of
illustrating portions of the earphone that form no part of the
claimed design.

1 Claim, 4 Drawing Sheets
